Des. 208,287
Patented Aug. 8, 1967

208,287

SODA DISPENSER

Nathan I. Tall, Tenafly, N.J., assignor to Kenco Products Corp., Englewood, N.J., a corporation of New Jersey

Filed Mar. 23, 1966, Ser. No. 1,599

Term of patent 14 Years

(Cl. D94—3)

FIG. 1

FIG. 2

FIG. 1 is a perspective view of a soda dispenser showing my new design; and

FIG. 2 is a plan view of said soda dispenser.

The undisclosed side of the soda dispenser is substantially the same in appearance as the sides shown, and the rear is flat and unornamented.

I claim:

The ornamental design for a soda dispenser, as shown and described.
